UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,800, dated June 1, 1880.

Application filed April 7, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

My present design is illustrated in the accompanying photograph, forming part of this specification, and to which reference is made in the following description.

The design is composed of crescents and curvilinear figures A and small squares B, placed alternately in rows and surrounded by curvilinear and geometric figures, as shown.

I claim—

The design for a carpet herein shown and described, consisting of the figures A and B and the surrounding curvilinear and geometric forms, as set forth.

In testimony whereof I have signed my name to this specification, in the presence of two subscribing witnesses, this 1st day of April, A D. 1880.

THOMAS J. STEARNS.
